UNITED STATES PATENT OFFICE.

JOHN W. WICKHAM, OF CLINTONVILLE, WISCONSIN.

RAIL-FROG CLAMP.

1,282,665.

Specification of Letters Patent. Patented Oct. 22, 1918.

Application filed July 26, 1918. Serial No. 246,947.

To all whom it may concern:

Be it known that I, JOHN W. WICKHAM, a citizen of the United States, residing at Clintonville, in the county of Waupaca 5 and State of Wisconsin, have invented certain new and useful Improvements in Rail-Frog Clamps, of which the following is a specification.

This invention is a rail frog clamp and 10 has for its principal object the production of an efficient means for firmly holding the frog adjacent a rail for allowing the frog to direct a wheel which has been de-railed into engagement with the rail.

Another object of this invention is the 15 production of a rail frog clamp which is of a flexible construction, thus being connected to the rail and also to the frog for firmly holding the frog adjacent the rail.

Another object of this invention is the 20 production of a rail frog clamp wherein a large chain is provided with a rail engaging hook while a small chain extends from the opposite end of the large chain 25 and is also provided with a gripping hook, whereby the gripping hook may pass the small chain through the hand hold opening in the frog, to draw the large chain through this opening and thus allow the 30 gripping hook to engage the large hook for holding the chain against displacement, thus holding the frog adjacent the rail.

One practical form or construction and 35 assembly of the present invention will be hereinafter described and is illustrated in the drawing, in which—

Figure 1 is a top plan view of a frog and a portion of the rail illustrating the 40 clamp in use.

Fig. 2 is a side elevation of the device in 45 use and

Fig. 3 is a transverse section taken on the line 3—3 of Fig. 1, the clamp being shown in elevation and illustrating the 50 use thereof.

In the referred embodiment of the present invention about to be described, it will be seen that the rail is indicated in general at 5 and the frog at 6. It will 55 be seen in Fig. 3 that frogs of this type are hollow and are of the camel back construction, being provided with a rib 7 thereon, thus allowing the wheel to ride upon the frog to be elevated and finally directed by the flange into engagement with the rail 5 it being also noted that the

frog is provided with a hand hold 8, thus allowing the same to be easily lifted and moved to a desired position.

The clamp comprises a chain of enlarged 60 links 9 having a flat rail engaging hook 10 upon one end thereof. The chain of small links 11 extends from the opposite end of the large links 9 and has a gripping hook 12 connected thereto. When the device is to be used, the frog is placed adjacent either side of the rail in the manner well known, it being obvious that the frog may be placed as near to the rail as desired, to either allow a sufficient space for 70 the wheel flange to pass between the rail and the frog or else to allow the wheel flange to be directed over the opposite rail, owing to the side of the rail upon which the wheel is de-railed.

At this time, the rail engaging hook 10 is slipped into engagement with the base of the rail, it being noted that this hook 10 is provided with an off-set lip 10' to allow the chain of large links 9 to be connected thereto without spreading the hook 10 from engagement with the base of the rail.

The gripping hook 12 may then be passed through the hand hold opening 8 85 of the frog 6 and obviously pull the small chain of links 11 through this hand hold and finally the chain of large links 9 will be drawn through this opening.

When the chain 9 has been drawn tautly, 90 the hook 11 may then be slipped into a gripping engagement with the chain, by gripping one link and allowing an adjacent link to bear thereon, thus positively binding the frog in a set position by the engagement 95 of the chain by the hooks, both with the rail and the frog. It is obvious the chain of small links will always retain the gripping hook 12 in convenient position for use, and will also constitute a guide for directing the chain of large links into the hand hold opening, also reducing the weight 100 of the structure. Therefore, although the chains provide a flexible structure which will allow the device to be very quickly adjusted when in use, it is non-elastic and for this reason will hold the frog against any tendency of accidental shifting, thus holding the frog to be properly braced, for directing a de-railed wheel into proper operative engagement with the rail.

The foregoing description and the draw-

ings have reference to what may be considered the preferred or approved form of my invention. It is to be understood that I may make such changes in construction 5 and arrangement and combination of parts, materials, dimensions, et cetera, as may prove expedient and fall within the scope of the appended claims.

Having thus fully described my invention, what I claim as new and desire to secure by Letters Patent, is:—

1. In combination with a rail and a frog having an opening, of a clamp member consisting of a flat rail engaging hook having 15 an off-set end, a chain of large links connected to the off-set end, thus allowing the hook to fit firmly upon the base of the rail, a chain of small links connected to the opposite end of the chain of large links, and 20 a gripping hook connected to the end of the chain of small links, whereby the gripping hook will cause the chain of small links to draw the chain of large links through the opening and then the gripping hook may 25 engage the chain of large links for holding the same in a taut condition, thus positively holding the frog in a set engagement with the rail.

2. In combination with a rail and a frog 30 having an opening, of a clamp member con-

sisting of a flat rail engaging hook having an off-set end, a chain connected to said off-set end, and a gripping hook connected to the remaining end of the chain, whereby the gripping hook will draw the chain 35 through the opening of said frog and then the hook will engage the same for holding the same in a taut condition, thus positively holding the frog in a set engagement with the rail. 40

3. In combination with a rail and a frog having an opening, of a clamp member consisting of a flat rail engaging hook, a chain connected to said rail engaging hook, and a gripping hook connected to the remaining 45 end of said chain, said gripping hook comprising a flat structure, whereby the gripping hook will draw the chain through the opening of said frog and then the gripping hook may engage the chain for holding the 50 same in a taut condition, thus positively holding the frog in a set engagement with the rail.

In testimony whereof I affix my signature in presence of two witnesses.

JOHN W. WICKHAM.
